[57] CLAIM

The ornamental design for a scuff guard for a vehicle fender, as shown and described.

DESCRIPTION

FIG. 1 is a perspective view of a scuff guard for a vehicle fender showing my new design, it being understood that the portions of the golf car shown in broken lines are for illustrative purposes only and form no part of the claimed design;

FIG. 2 is an enlarged top plan view of my new design; FIG. 3 is an enlarged left side elevational view thereof; FIG. 4 is an enlarged right side elevational view thereof;

FIG. 5 is an enlarged bottom plan view thereof; FIG. 6 is an enlarged front elevational view thereof; and,

FIG. 7 is an enlarged rear elevational view thereof.
